UNITED STATES PATENT OFFICE.

JOSEPH B. VICTOR, OF CHICAGO, ILLINOIS, ASSIGNOR TO VICTOR MANUFACTURING & GASKET CO., OF CHICAGO, ILLINOIS, A CORPORATION OF ILLINOIS.

AUDIBLE SIGNALING DEVICE.

1,237,842.

Specification of Letters Patent. Patented Aug. 21, 1917.

Application filed November 26, 1915. Serial No. 63,515.

To all whom it may concern:

Be it known that I, JOSEPH B. VICTOR, a citizen of the United States, residing at Chicago, in the county of Cook and State 5 of Illinois, have invented certain new and useful Improvements in Audible Signaling Devices, of which the following is a specification.

My invention relates to audible signals, 10 and particularly to the type of signals in which the sound is produced by the operative contact of an irregular surface against a vibratory diaphragm. The invention has for its object to simplify the construction, 15 and operation of a device of the above character; reduce the cost of manufacturing the device by having it composed of a minimum number of parts; and to provide certain arrangements whereby the various parts may 20 be easily assembled and readily adjusted or repaired.

The device of my invention is intended more particularly as a warning device or horn for automobiles and one of the special 25 objects of the invention is to provide an automobile horn which will be compact in form; and which may be easily manipulated to produce a loud, penetrating sound of considerable duration.

30 The invention has for further objects such other new and improved constructions and combinations of parts to be hereinafter more specifically described and claimed.

The preferred embodiment of the invention 35 is shown in the accompanying drawing in which like characters of reference designate corresponding parts, and in which—

Figure 1 is a side elevation of my improved signaling device.

40 Fig. 2 is a fragmentary sectional view of the same illustrating the construction and arrangement of the operative parts, and

Fig. 3 is a cross sectional view taken on line 3—3 of Fig. 1, looking in the direction 45 indicated by the arrows.

Referring to the drawing, 10 designates the mouth piece of my improved signaling device, the outer end of which is formed with an elongated flared portion 11. This 50 particular construction of the mouth piece is immaterial, as any well known construction may be used that may be found to be most suitable for the manner and place in which the device is applied. The inner end

of the mouth piece is preferably secured 55 within an annular opening 12 of a dish-shaped head plate 13 of the casing 14 by means of a bead 15 and flange 16, the latter being pressed down tightly around the inner edge of the opening 12. The casing 14 is 60 formed with a slot 17 and with suitable bearings for the shaft 18, the shaft being preferably secured in the bearings against rotation. The shaft may be held against any lateral movement in the casing by any suitable 65 means. As a means for performing this function, I have shown the ends of the shaft hammered over so as to form heads 19. A hand wheel 20 is loosely mounted on the shaft 18, the diameter of the wheel 20 being 70 preferably large enough so that its perimeter will project out of the casing 14 through the slot 17. The hand wheel 20 is preferably composed of a central ring portion 21 of hardened metal which is formed on its outer 75 periphery with transversely extending ridges or teeth 22. The ring portion 21 is cased in or otherwise embedded in a softer metal which forms the body of the wheel. The metal which incases the hard metal 80 ring 21 and forms the main body of the wheel extends preferably beyond the outer edge of the ring 21 so as to provide an annular groove 23. From the construction 85 of the wheel 20 thus far described, it will be seen that the periphery of the wheel contains more weight than the center. The distribution of weight in this manner gives the wheel more momentum and makes it more 90 adapted for the purpose for which it is intended, as will be hereinafter set forth. The inner periphery of the ring 21 is 95 notched as at 24 so that the ring will be securely anchored to the main body of metal. The portion of the wheel which projects out of the casing 14 has its side surfaces formed preferably with radial grooves 26 which serve as suitable finger grips for the operator. The hub 27 is cored out, as indicated at 28, so as to reduce the friction between the wheel and shaft, and is held in its central position on the shaft by means of the sleeves 29. Interposed between the head plate 13 and the casing 14 is a resonant member 30 which is shown in the drawing as a thin disk or diaphragm having its extremity clamped between the flanges 31, 32 of the head plate and casing, respectively.

A threaded stud 33, formed with a tapered nose 34, is screwed into the center of the diaphragm 30 so that the nose 34 will extend into the groove 23 of the wheel and engage the teeth 22. The stud 33 carries a jam-nut which may be screwed down against the outer surface of the diaphragm to lock the stud in any adjusted position. The entire device is preferably supported on the attaching bracket 36.

In operation, the operator grasps or draws his hand across the periphery 25 of the hand wheel 20 so as to impart rotation thereto. The teeth 22 engaging the nose 34 of the stud 33 while the wheel is rotating, vibrate the diaphragm 30 so as to produce the sound. The wheel will rotate for a short time after the operator has removed his hand, due to its momentum and to the fact that the friction between the wheel and shaft 18 is minimized. This spinning or fly-wheel effect is increased by reason of the wheel being relatively large in diameter and the distribution of metal so as to give the wheel more weight near its periphery. The stud 33 is preferably adjusted so that the frictional engagement between the nose 34 of the stud and toothed portion of the wheel will prevent the accidental rotation of the wheel which might otherwise occur should the device receive a sudden jar such as would be common when applied to motor driven vehicles. It will be seen that the wheel 20, which I have termed a hand wheel because it is rotated by direct contact of the hand of the driver, is the element which, by rubbing against the resonant member, or the teeth thereon, sets the same in vibration. There is no intermediate train of gears or other mechanism. For this reason the wheel may be rotated in either direction, as may be most convenient. Furthermore, the device is, for this reason, very simple, positive, compact and durable. The toothed portion of the perimeter of the wheel is of relatively large diameter so that wear on the teeth is minimized.

While I have described my invention in its preferred embodiment, it will be understood that certain modifications might be made without departing from the spirit of my invention.

I claim:

1. An audible signaling device for vehicles comprising a resonant diaphragm provided with a stud, a hand wheel provided with teeth around its periphery to engage said stud, said hand wheel being of sufficient diameter and weight so that it will rotate by inertia after a movement of rotation is imparted to it, and a rigid support for said diaphragm providing bearings for revolubly mounting said hand wheel so that in operation it will revolve freely out of contact with everything except the stud and said bearings.

2. In a device of the character described, the combination of a resonant member, and a hand wheel formed with a roughened surface within its perimeter adapted to engage said resonant member so as to vibrate the same.

3. In a device of the character described, the combination of a resonant member, and a hand wheel formed with a groove and provided with a toothed surface wholly within said groove adapted to engage said resonant member so as to vibrate the same.

4. In a device of the character described, the combination of a resonant member, and a hand wheel formed with a peripheral groove and provided with a toothed surface wholly within said groove adapted to engage said resonant member so as to vibrate the same.

5. In a device of the character described, the combination of a resonant member, and a hand wheel formed with a peripheral groove and provided with a toothed surface within said groove adapted to engage said resonant member so as to vibrate the same, the outer edge of the teeth of said toothed surface being within the perimeter of said wheel.

6. In a device of the character described, the combination of a resonant member, and a hand wheel which contacts directly with said resonant member to vibrate the same; said hand wheel being formed with a peripheral channel and provided with a toothed element seated in said channel within the perimeter of the wheel so as to engage said resonant member.

7. In a device of the character described, the combination of a resonant member, and a hand wheel which contacts directly with said resonant member to vibrate the same; said hand wheel being formed with a peripheral channel and provided with a toothed ring seated in said channel which engages said resonant member.

8. In a device of the character described, the combination of a resonant member and a hand wheel which contacts directly with said resonant member to vibrate the same; said hand wheel being formed with a channel and provided with a toothed ring seated in said channel which engages said resonant member, the diameter of said ring being less than the diameter of said hand wheel.

9. In a device of the character described, the combination of a resonant member and a hand wheel which contacts directly with said resonant member to vibrate the same; said hand wheel being formed with a peripheral channel and provided with a toothed ring seated in said channel which engages said resonant member, the diameter of said ring being less than the diameter of said hand wheel.

10. In a device of the character described,

the combination with a casing formed with a slot, of a hand wheel mounted in said casing and projecting therefrom through said slot and formed with a peripheral groove 5 and provided with teeth in said groove, a resonant diaphragm disposed within said casing, and a stud screwed into said dia-

phragm so as to be adjustable toward said hand wheel to take up wear; said hand wheel being formed with radially extending 10 grooves on its side surfaces so as to provide finger grips for the operator.

JOSEPH B. VICTOR.
